UNITED STATES PATENT OFFICE.

ALVAH CLARENCE TEBBETTS, OF BOSTON, MASSACHUSETTS.

LIP-GUARD AND PROTECTOR.

SPECIFICATION forming part of Letters Patent No. 622,564, dated April 4, 1899.

Application filed September 30, 1898. Serial No. 692,299. (No model.)

To all whom it may concern:

Be it known that I, ALVAH CLARENCE TEBBETTS, of Boston, in the county of Suffolk and State of Massachusetts, have invented 5 certain new and useful Improvements in Lip-Guards and Protectors, of which the following is a description sufficiently full, clear, and exact to enable those skilled in the art to which it appertains or with which it is most 10 nearly connected to make and use the same.

This invention has for its object the provision of a lip-guard and protector adapted to be placed over the edge of a drinking cup or glass, so as in drinking from the cup or glass 15 to guard the lips from coming into contact with the latter and as a consequence protect the person drinking from being poisoned or otherwise detrimentally affected by any substance left on the glass by the person first 20 drinking therefrom.

It is well known that a person cannot put a cup or glass to his or her mouth and drink therefrom without to a greater or less extent 25 depositing or leaving upon the glass where the mouth was applied some of the mixed secretions of the salivary glands and the mucous membrane of the mouth, so that to persons sensible of this fact it is repulsive to drink after another from the same cup or glass with- 30 out first cleansing it. Again, in case where a person drinking from a cup or other vessel 35 is diseased or has irritated or diseased lips such cup is rendered a positive danger hygienically to another drinking after them or at least from the same place or point of the same vessel without first cleansing the edge 40 of the cup. Moreover, it is known that it is impracticable in some places and under some circumstances to furnish individual cups to

45 persons who wish to drink or to cleanse the cup after each individual has drank therefrom. This is the case generally, for example, with people traveling in railway-cars and wherever water is offered for drink publicly.

45 It is to overcome the objections and forbiddings mentioned that I have provided my invention, which consists of a lip-guard and protector for drinking vessels, comprising a piece of suitable material bent to form two 50 members, one adapted to extend inside the cup and the other outside, with the line of bending adapted to rest upon the upper edge

of the cup and the bending being of such a character as to give each member the form substantially that of a segment of a circle, 55 and providing a packing within the bend to prevent liquid in the cup from running over the upper edge below the guard, the free ends of the two members flaring outwardly, all as is hereinafter fully set forth and explained. 60

Reference is to be had to the annexed drawings, and to the letters marked thereon, forming a part of this specification, the same letters designating the same parts or features, as the case may be, wherever they occur. 65

Of the drawings, Figure 1 is a perspective view of a drinking glass or cup having my invention applied thereto. Fig. 2 is a plan view of the invention. Fig. 3 is a view of the invention looking at it from the inside. Fig. 4 70 is a substantial side view of the invention. Fig. 5 is a vertical sectional view of the invention.

In the drawings, *a* designates the body part or member of my invention, and *b* is the inside or lip member. The two members are formed from a sheet of suitable material bent or molded so as to integrally connect them along the line *c*, where a substantial U-shaped form may be given to the device. It would 75 be within the scope of the invention, however, to make the two members in separate pieces and suitably unite them along the line *c*. A curvature is given to both members *a* and *b* and the connecting portion *c* in horizontal 80 cross-section, such curvature being substantially the segment of a circle, so that when the device is placed upon the edge of a cup *d*, as shown in Fig. 1, with the inner lip *b* inside of the cup and the outer member *a* on 85 the outside, it will fit upon the edge of a cup or glass, as shown.

The members *a* and *b*, in addition to being curved slightly in cross-section, are curved from their point of junction slightly outward, 95 or, at any rate, it has been found advantageous in some instances to have the two members *a* and *b* slightly diverge from their point of junction in opposite directions to their extremities. It would not be without the scope 100 of my invention, however, to have the members *a* and *b* extend downward from their point of junction in a plane substantially parallel to each other. Such construction would,

it must be said, be likely to make it a little more difficult to apply the device to the upper edge of a glass or cup than it would if the members were made to diverge, as before 5 stated.

In some instances I render the inner member *b* foraminated by making holes *e* therein, as shown, so that when the device is in use the inner member will act as a substantial 10 strainer to the liquid in the cup or glass that may be drank therefrom.

It is to be remarked that the form of the bend given to the device along the line *c* is preferred to be such that in virtue of it when 15 the device is placed upon the edge of a glass, as shown in Fig. 1, it will be packed along the line of the edge of the glass in such manner as to prevent the liquid from running over the edge of the glass between the latter 20 and the guard and down outside. In some instances I prefer, however, to secure a strip of packing *f* along one side of the bend *c* and on the inside of the device, against which packing the edge of the glass or cup may be 25 brought, so as to make sure of packing along said line to prevent the overflow of water or other liquid, as stated.

Any desired outline may be given to the members *a* and *b*. That shown in the drawings has been found to be serviceable and not 30 unsightly. I do not, by the way, confine myself to such outline or form.

It will be sufficient for my invention to have the device composed of two members united 35 as stated and adapting the device to be placed

upon the edge of a glass or cup, as shown in Fig. 1, and subserving the purpose of guarding the lips of the user of the glass from coming into contact with the latter and guarding him or her against the dangers and objections 40 to drinking from a vessel from which another has previously drank before the vessel has been cleansed.

Having thus explained the nature of the invention and described a way of constructing and using the same, though without attempting to set forth all of the forms in which it may be made or all of the modes of its use, it is declared that what is claimed is—

1. A lip-guard and protector for drinking 50 vessels bent or molded along the line *c* and forming the parts or members *a*, *b*, each member being given the form of a segment of a circle in cross-section, a packing being secured in the bend, and the two members flaring outwardly in opposite directions at their free ends as described.

2. A lip-guard and protector for drinking vessels composed of the members *a* and *b* connected by a substantially U-shaped bend *c* in 6c cross-section and a packing *f* secured in said bend.

In testimony whereof I have signed my name to this specification, in the presence of two subscribing witnesses, this 3d day of September, A. D. 1898.

ALVAH CLARENCE TEBBETTS.
